(57) **CLAIM**

The ornamental design for a nestable drum, as shown and described.

DESCRIPTION

FIG. 1 is a left, front and top perspective view of a first embodiment of a nestable drum;

FIG. 2 is a right, back, and bottom perspective view of the nestable drum of FIG. 1;

FIG. 3 is a back elevational view of the nestable drum of FIG. 1;

FIG. 4 is a front elevational view of the nestable drum of FIG. 1;

FIG. 5 is a left elevational view of the nestable drum of FIG. 1;

FIG. 6 is a right elevational view of the nestable drum of FIG. 1;

FIG. 7 is a top plan view of the nestable drum of FIG. 1;

FIG. 8 is a bottom plan view of the nestable drum of FIG. 1;

FIG. 9 is a left, front and top perspective view of a second embodiment of a nestable drum;

FIG. 10 is a right, back, and bottom perspective view of the nestable drum of FIG. 9;

FIG. 11 is a back elevational view of the nestable drum of FIG. 9;

FIG. 12 is a front elevational view of the nestable drum of FIG. 9;

FIG. 13 is a left elevational view of the nestable drum of FIG. 9;

FIG. 14 is a right elevational view of the nestable drum of FIG. 9;

FIG. 15 is a top plan view of the nestable drum of FIG. 9;

FIG. 16 is a bottom plan view of the nestable drum of FIG. 9;

FIG. 17 is a left, front and top perspective view of a third embodiment of a nestable drum;

FIG. 18 is a right, back, and bottom perspective view of the nestable drum of FIG. 17;

(Continued)

FIG. 19 is a back elevational view of the nestable drum of FIG. 17;
 FIG. 20 is a front elevational view of the nestable drum of FIG. 17;
 FIG. 21 is a left elevational view of the nestable drum of FIG. 17;
 FIG. 22 is a right elevational view of the nestable drum of FIG. 17;
 FIG. 23 is a top plan view of the nestable drum of FIG. 17;
 FIG. 24 is a bottom plan view of the nestable drum of FIG. 17;
 FIG. 25 is a left, front and top perspective view of an fourth embodiment of a nestable drum;
 FIG. 26 is a right, back, and bottom perspective view of the nestable drum of FIG. 25;
 FIG. 27 is a back elevational view of the nestable drum of FIG. 25;
 FIG. 28 is a front elevational view of the nestable drum of FIG. 25;
 FIG. 29 is a left elevational view of the nestable drum of FIG. 25;
 FIG. 30 is a right elevational view of the nestable drum of FIG. 25;
 FIG. 31 is a top plan view of the nestable drum of FIG. 25;
 FIG. 32 is a bottom plan view of the nestable drum of FIG. 25;
 FIG. 33 is a left, front and top perspective view of a fifth embodiment of a nestable drum;
 FIG. 34 is a right, back, and bottom perspective view of the nestable drum of FIG. 33;
 FIG. 35 is a back elevational view of the nestable drum of FIG. 33;
 FIG. 36 is a front elevational view of the nestable drum of FIG. 33;
 FIG. 37 is a left elevational view of the nestable drum of FIG. 33;
 FIG. 38 is a right elevational view of the nestable drum of FIG. 33;
 FIG. 39 is a top plan view of the nestable drum of FIG. 33; and
 FIG. 40 is a bottom plan view of the nestable drum of FIG. 33.
 The broken lines in the figures show portions of the nestable drum which form no part of the claimed design.
